Primary Examiner — Wan Laymon

CLAIM

The ornamental design for a laboratory apparatus, as shown and described.

DESCRIPTION

FIG. 1 is a front perspective view of a laboratory apparatus showing our design;

FIG. 2 is a top view thereof; and,

FIG. 3 is a left side view thereof, the right side is a mirror image of the left side.

The broken lines shown in the figures represent portions of the laboratory apparatus that form no part of the claimed design.
